Primary Examiner — Cathron Brooks*Assistant Examiner* — Celse Moore, Jr.(74) *Attorney, Agent, or Firm* — Blakely Sokoloff Taylor & Zafman LLP(57) **CLAIM**

The ornamental design for a three wheeled vehicle, as shown and described.

DESCRIPTION

FIG. 1 is a first perspective view of the three wheeled vehicle; FIG. 2 is a second perspective view thereof; FIG. 3 is a front view thereof; FIG. 4 is a rear view thereof; FIG. 5 is a first side view thereof; FIG. 6 is a second side view thereof; FIG. 7 is a top view thereof; and, FIG. 8 is a bottom view thereof.

The broken line showing of the wheels and portions of the bottom plan view are for the purpose of illustrating portions of the vehicle that form no part of the claimed design.

1 Claim, 8 Drawing Sheets(56)
